UNITED STATES PATENT OFFICE.

NATHAN H. SUREN, OF NEEDHAM, MASSACHUSETTS, ASSIGNOR, BY MESNE ASSIGNMENTS, TO THE GAMEWELL COMPANY, OF NEWTON, MASSACHUSETTS, A CORPORATION OF MASSACHUSETTS.

STARTING ATTACHMENT FOR SIGNAL TRANSMITTERS.

Application filed July 8, 1921. Serial No. 483,222.

To all whom it may concern:

Be it known that I, NATHAN H. SUREN, residing at Needham, in the county of Norfolk and Commonwealth of Massachusetts, have invented certain new and useful Improvements in Starting Attachments for Signal Transmitters, of which the following is a specification.

This invention relates to starting attachments for signal transmitters such as, for example, auxiliary tripping mechanism for fire alarm street boxes; and more particularly to the type of such attachments which is arranged to act to trip its associated transmitter in response to actuation of a distant initiating station, and to be thereupon rendered unresponsive to further actuation of any such distant station until such attachment has been manually reset or restored. This invention is in the nature of an improvement upon the transmitter starting attachment disclosed by my co-pending application filed April 4th, 1919, Serial No. 287,502, Patent No. 1,503,439, issued July 29th, 1924.

An object of this invention is to provide locking means for an indicator associated with such an attachment whereby such indicator will be locked against accidental displacement such as would cause a false "set" or "restored" indication, and whereby such indicator will be automatically restored to normal position when the restoring member has been fully actuated and the starting attachment is ready for action.

Another object is to provide locking means whereby such an attachment may be partially restored for the purpose of disclosing the condition of the controlling circuit thereof, without causing the formulation of any signal in the associated main line circuit in the event that such controlling circuit is abnormally conditioned.

Another object is to provide associated means whereby such a starting attachment will not act in response to its controlling circuit (other than for the purpose of indicating the condition of said circuit) unless the motive power of said attachment is adjusted to cause a complete operative cycle thereof.

A further object is to provide means

whereby continued abnormal conditioning of the auxiliary loop will result in the formulation by such an attachment of a signal in the main line circuit, which signal will be of such a character as to cause response of main line signal manifesting devices distinctive both from that which results from a broken main line circuit and that which results from actuation of a main line transmitter.

Still other objects, together with their inherent advantages, will be in part obvious and in part specifically set forth in the following specification and more fully pointed out in the claims.

For the purpose of illustrating the various features of this invention, one specific embodiment thereof is shown by the annexed drawings and hereinafter more fully described, but it will be understood that this invention is adapted for other embodiments within the scope of the appended claims.

Similar reference characters denote like parts throughout the accompanying drawings, in which—

Figure 1 is a diagrammatic representation of a signaling circuit including fire alarm boxes of a conventional type, and showing, in detail, the actuating mechanism of a distant auxiliary initiating station and the electrical connections between a group of such stations and circuit controlling and responsive parts of an auxiliary fire alarm master box controlled thereby and constructed in accordance with this invention;

Fig. 2 is a fragmentary view of the magnet and certain of the contacts of the starting attachment of Fig. 1, together with certain of the parts associated therewith;

Fig. 3 is a fragmentary view of the remaining starting attachment contacts of Fig. 1, together with associated operating mechanism therefor;

Fig. 4 is a right side elevation of the magnet and mechanism provided for the actuation of the starting attachment contacts shown in Fig. 1; portions of certain parts being broken away and shown in section for the purpose of more clearly disclosing the construction and arrangement of said attachment;

Fig. 5 is a rear view of certain of the parts of Fig. 4, showing the normal positions thereof and their relation to the parts shown in Fig. 3;

6 Figs. 6, 7 and 8 are views of certain of the parts shown in Fig. 5 taken at various operative stages thereof.

7 Fig. 9 is a sectional view of certain of the parts of Fig. 8, taken on a line disposed at 10 right angles to the pin 160 of Fig. 8; and

8 Fig. 10 is a view showing certain of the parts of Figs. 3 and 8, and also illustrating an alternative arrangement to be referred to.

15 Referring to Fig. 1; the battery A, bell B, register C, and typical fire alarm boxes D, E and F are serially connected in the main line circuit comprising the conductors 21, 22, 23, 24, 25 and 26; thus representing 20 a typical municipal fire alarm circuit.

25 The box or transmitting station F is provided with terminals 27, 28 and 29; the conductor 23 being connected to the terminal 29, and the conductor 24 being connected to the terminal 27.

30 An auxiliary station loop comprising the conductors 30, 31, 32, 33 and 34 is connected to the terminals 28 and 29 and serially connects the auxiliary signal initiating stations 35 G, H, I and J, the mechanism of which stations are identical; hence the disclosure of the mechanism of the station H is believed to suffice for all of such stations. The mechanism of each of said auxiliary stations 40 comprises an arm 35, pivoted at 36, and the outer end of which is arranged to cooperate with the contact buttons 37, 38 and 39; the spring 40 being so applied to said arm 35 as to tend to swing the free end thereof in- 45 to engagement with the stop 41, which stop is so positioned that when the arm 35 is brought into engagement therewith said arm will rest upon the button 39.

50 A latch 42, pivoted at 43, is mounted in such relation to the pin 44 carried by the arm 35 that, when said arm is resting upon the button 37, said stop may serve to hold said arm from movement in response to the spring 40. A push rod 45 connects with the latch 42, and an end of said rod projects through a wall of the case 46 for the purpose of facilitating manual actuation of said latch for the disengagement thereof from the pin 44.

55 A dashpot 47 is mounted below the arm 35, one member of said dashpot being secured to said arm and the other member of said dashpot being secured to the case 46 or other stationary part of the station H.

60 A corresponding auxiliary loop comprising the conductors 30', 32', 33' and 34' and including the stations 'G', 'I' and 'J' is shown similarly connected to the transmitting box D.

65 The main line code signal transmitter of

station F comprises a code wheel 50, a signaling lever 51 engaging said code wheel, signaling contacts 52 controlled by said lever, a non-interference magnet 53, and a controlling lever 54 one end of which carries the armature 55 which cooperates with said non-interference magnet 53 and the other end of which cooperates with the signaling lever 51 so as to afford a well known type of non-interference. Suitable propelling mechanism (not shown) is provided for the actuation of the code wheel 50, which propelling mechanism may be of any well known type of normally wound fire alarm box clockwork, and includes means for controlling the running of such clockwork, such as the typical notched track 56 with which the detent 57 is normally engaged for the purpose of holding such train at rest.

70 The detent 57 is pivoted at 58 and moves with an arm 59. A link 60 is hinged to the free end of said arm 59 for the purpose of swinging the detent 57 out of engagement with the track 56, as hereinafter more fully explained.

75 The main line code signal transmitter just described is mounted in an inner round case 61, which is contained in the outer case 61' of the transmitting box F. Said outer case also contains a starting attachment 80 comprising the parts indicated by Figs. 2, 3, 4 and 5; however, in the interests of clearness, Fig. 1 merely illustrates diagrammatically the tripping magnet 62, the starting attachment contacts 63, 64, 65 and 66 and the indicator plate 67, all of which parts are shown in a larger scale and in connection with other parts of said attachment in other figures of the drawings.

85 The conductor 68 extends from the terminal 27 to one end of the winding of the non-interference magnet 53; the conductor 69 extends from the other end of the winding of said magnet 53 to one member of the signaling contacts 52; the conductor 70 extends from the other member of the signaling contacts 52 to the starting attachment contact 63; the conductor 71 connects the contacts 64 and 66 to the terminal 28; the conductor 72 connects the contact 65 to the terminal 29; the conductor 73 connects one end of the winding of the electromagnet 62 to the conductor 71; and the conductor 74 connects the other end of said winding to the conductor 72. Referring now more particularly to Fig. 2: the lever 80 is loosely journaled on the shaft 81. The insulating pin 82 is mounted in the free end of said lever 80, so that, when the said lever is normally positioned (as indicated by solid lines in Fig. 2) said pin 82 will engage contact 65 and lift said contact away from the contact 66 for a purpose which will be hereinafter more fully explained.

90 One end of the spring 83 is secured to the

pin 84 carried by the lever 80, and the other end of said spring is secured to the abutment plate 85 at 86, so that said spring will constantly urge said lever toward the abnormal position thereof, as indicated by dotted lines in Fig. 2. The upper edge of the abutment plate 85 serves as a stop for the movement of the lever 80 in response to the spring 83.

Referring now more particularly to Fig. 3: the lever 90 is fixed upon the shaft 91, and said lever carries near the free end thereof an insulating pin 92 which is so positioned with relation to the projection 93 depending from the contact 63 that, when the shaft 91 is suitably rotated, the pin 92 will be moved past said projection 93 and will thereby momentarily move the contact 63 away from the contact 64 for a purpose which will be hereinafter more fully explained.

Referring now more particularly to Fig. 4: the main shaft 100 is provided with a squared end 101 adapted for engagement by a winding key or other suitable setting member, said shaft being journaled in the frame plates 102 and 103. A boss 104 is fixed upon the shaft 100, and the inner end of a main spring 105 is secured to said boss. The notched disk 106 (see also Figs. 2 and 3) is fixed upon the shaft 100 in suitable relation to a dog 107, so that the free end of said dog may engage a wall of a notch provided in said disk for the purpose of serving as a holder for retaining energy stored in the spring 105 by the rotation of the shaft 100.

The dog 107 is loosely journaled upon the shaft 91, and said dog carries an arm 108 which projects into the path of the pin 84, so that when the shaft 100 is rotated so as to force the free end of the dog 107 out of the notch in the disk 106, said end 108 will be brought into engagement with said pin 84 and thereby swing the arm 80 toward its normal position. A cam faced arm 109 is also loosely journaled upon the shaft 91; the outer end of said arm is normally supported by the pin 110 carried by the arm 80, and a slot is provided near the free end of said arm for receiving said pin 110 when the lever 80 is in its normal position.

The disk 106 is so formed that, when moved from its normal position, the rise thereof which engages the free end of the dog 107 will quickly move said dog away from the shaft 100 far enough to cause the arm 108 to act through the pin 84 to swing the lever 80 into engagement with the contact 65, and thereby move said contact away from the contact 66; but insufficiently to bring the pin 110 into register with the slot provided therefor in the arm 109. The periphery of the disk 106, from the outer end of the rise just described to a point adjacent to the holding face of the notch in said face, is substantially concentric with the shaft 100; and a further rise is provided in the

periphery of said disk between the end of said concentric portion and the holding face of the notch formed therein whereby the dog 107 will be moved still further from the shaft 100 and will thereby swing the arm 80 to its fully restored or normal position, so as to bring the pin 110 in register with the notch in the arm 109, just before the notch in said disk is presented to the end of the dog 107 during clockwise rotation of the shaft 100.

A spring 111 is provided for holding the free end of the arm 109 in engagement with the pin 110 and for holding the free end of the dog 107 in engagement with the disk 106; one end of said spring 111 is secured to the pin 112 which is carried by the arm 109, and the other end of said spring is secured to the pin 113 which is carried by the arm 108 which moves with the dog 107.

A shield 114 is carried by the lever 80 and is of such form that, when said lever is normally positioned, said shield will cover a part of the legend of the indicator plate 67, and so that when said arm is abnormally positioned said shield will not cover any part of said legend.

A flexible latch 115 is secured to the dog 107; the outer end of said latch is so formed that when said dog is normally positioned said end will be disposed in the path of the pin 116 carried by the arm 80, so as to prevent movement of said arm from the abnormal to normal position thereof, and so that, when the dog 107 has been forced out of the notch in the disk 106, such end of the latch 115 will be swung downwardly and will thereby permit the lever 80 to be moved from its abnormal to its normal position. The upper edge of the portion of the latch 115 with which the pin 116 is normally engaged is flared inwardly (as best shown in Fig. 4) so that said latch will be sprung rearwardly by the pin 116 when the free end of the dog 107 moves into the notch in the disk 106 while the lever 80 is in its normal position.

The drum 117 is loosely journaled upon the shaft 100 and encloses the boss 104 and the main spring 105, the outer end of the main spring 105 being attached to said drum at 118. A portion of the periphery of the drum 117 has the gear teeth 119 formed therein; the cam 120 is carried by the front face of said drum, and the track 121 and wedge shaped block 122 are carried by the rear side of said drum. The cam 120 is of such width that it projects into the path of the lever 90 (as best shown by Fig. 4) so that said cam may act, at certain times, to move said lever toward the normal position thereof, as will be hereinafter more fully explained.

The lever 123 (see Fig. 3) is loosely journaled on the shaft 81, and the free end of

said lever projects into the path of the cam 120 for actuation thereby. One end of the spring 125 is secured to the lever 123 at 126, and the other end of said spring is secured 5 to the abutment 85 at 87, so that said spring constantly urges the free end of the lever 123 toward the cam 120.

The pin 130 (see Fig. 3) is carried by the lever 123 and is so positioned thereon with 10 relation to the shouldered terminal 131 carried by the link 60 that, if said terminal is in the path of said pin when the rise of the cam 120 swings the lever 123 against the tension of the spring 125, said pin 130 will 15 thrust the link 60 to the left and thereby swing the detent 57 out of engagement with the track 56. A spring 132 is so applied to the link 60 as to tend to hold the terminal 131 in engagement with the pin 130 and 20 thereby maintain the driving shoulder of said terminal in the path of said pin.

The pin 130 projects into the path of the hook arm 109 (see Fig. 2) so that, whenever the cam 120 swings the lever 123 against 25 the tension of the spring 125, the pin 130 will act against the slanting face of the arm 109 to swing said arm upwardly so as to release the pin 110 therefrom and thus permit the lever 80 to be swung to its abnormal 30 position by the spring 83.

Referring now more particularly to Fig. 5; the pinion 133 is mounted upon a shaft 134 for engagement by the gear teeth 119 of the drum 117. The escapement wheel 135 is 35 also mounted upon the shaft 134 and moves with said pinion 133.

The escapement pallet 136 and the pendulum 137 are fixed upon the shaft 138 for regulating the speed of rotation of the wheel 40 135.

A latch piece 139 is loosely journaled upon the shaft 138, and an end 140 of said piece is adapted to engage the pin 141, carried by the escapement wheel 135, for the 45 purpose of arresting the rotation thereof; said end 140 being so formed that when engaged by the pin 141 said pin will tend to move said end out of the path thereof. The spring 142 is so applied to the piece 139 as 50 to tend to swing the end 140 into the path of the pin 141.

A lever 143 is fixed upon the shaft 91 (see also Fig. 4). The arm 145 of said lever 143 is adapted, when in one position, to engage 55 the pin 146 carried by the piece 139 so as to prevent movement of the end 140 of said piece out of the path of the pin 141, and when in another position to withdraw said arm 145 from the path of said pin 146 so 60 as to permit the end 140 to move out of the path of the pin 141.

A spring 147 is so applied to the lever 143 as to tend to swing the arm 145 into the path of the pin 146. The arm 148 of the lever 65 143 carries a lug 149; which lug is disposed

in the plane of the track 121 and the block 122 for cooperation therewith in a manner which will be hereinafter more fully explained. The arm 150 is also fixed upon the shaft 91, and the free end of said arm extends into the path of the rocker bar 151.

The electromagnet 62 comprises cores having the extended pole pieces 152, 152. The armature 153 is fixed upon one end of the rocker shaft 154 and the rocker bar 151 is 75 fixed upon the other end of said shaft. The respective ends of the armature 153 are presented to opposite sides of the pole pieces 152, 152, so that the pull imparted to said armature incident to the energization of the magnet 62 will act through the shaft 154 to swing an end of the rocker bar 151 toward the arm 150. A spring 155 is so applied to the rocker bar 151 as to tend to swing the coengaging end of said bar away from the 80 arm 150.

The face of the arm 150 which is nearest to the track 121 is extended above the shaft 91, so as to form an ear 156; said ear extends adjacent to the path of the pin 157 which is carried by the drum 117, so that said ear may be engaged by said pin for a purpose which will be hereinafter more fully explained.

The pin 157 is so positioned with relation 95 to the notch 158 which is formed in the track 121 that during the rotation of the drum 117, said notch is first presented to the lug 149, said pin 157 will engage the ear 156 and swing the arm 150 and parts moving therewith so as to carry the arm 145 into the path of the pin 146; thereby swinging the lug 149 outwardly through the notch 158 and causing the free end of the arm 150 to act through the rocker arm 151 and shaft 100 to swing the ends of the armature 153 100 away from the pole pieces 152, 152.

The formation and arrangement of the ear 156, the pin 157, the end 140 and the pin 141 with relation to the operating ratio 110 between the drum 117 and the pinion 133 is such that said pin 141 will not be in position to engage the end 140 while the pin 157 is in position to engage the ear 156; and such that, immediately after said pin 157 115 has moved out of the path of the ear 156, the pin 141 will reach the position where it may be engaged by the end 140.

The dog 159 is loosely journaled upon the shaft 100, and the free end of said dog extends into the path of the block 122 carried by the drum 117. A pin 160 is fixed in the shaft 100, and extends through slots in the boss of the dog 159 so as to permit said dog to rotate around said shaft an 120 angular distance somewhat greater than the angle subtended by the outer face of the block 122 plus that subtended by the portion of the dog 159 disposed in the path of said block, to the end that slightly more 125 130

than one complete revolution may be imparted to the shaft 100 without rotating the drum 117.

The segmental piece 161 is loosely journaled upon the boss of the dog 159, being held in place thereon by the pin 160. A pin 162 is carried by the piece 161, and said pin projects into the path of the dog 159 for the purpose of suitably limiting the rotative movement of said piece with relation to said dog. A spring 163 (see Fig. 6) is connected between the dog 159 and the piece 161 so as to tend to turn said piece counterclockwise in relation to said dog and thereby maintain said pin 162 in engagement with a side of said dog.

A projection 164 carried by the arm 148 is so situated with relation to the circumferential face of the piece 161 that, when the lug 149 is inside of the track 121 and the arm 145 is out of the path of the pin 146, said projection will be disposed in the path of said piece 161; and so that when the circumferential face of said piece is interposed between said projection 164 and the shaft 100 the lever 143 will be held against such movement as would withdraw the arm 145 from the path of the pin 146.

The ear 94 moves with the lever 90, (see Fig. 3) and is so positioned with relation to the link 60 that, when said lever is normally positioned, the shoulder of the terminal 131 may be so positioned as to be disposed in the path of movement of the pin 130; and so that, when said lever is so abnormally positioned as to bring the pin 92 into engagement with the projection 93, said ear 94 will swing the link 60 downwardly against the tension of the spring 132 so as to carry the shoulder of the terminal 131 out of the path of the pin 130.

From the foregoing it will be apparent that the lever 143 and the parts moving therewith constitute a controlling member which, in cooperation with a retarded operated member comprising the drum 117 and parts carried thereby, provide a determining device; that such controlling member is governed by the tripping magnet 62 for the purpose of initiating the operating cycle of this attachment; that said retarded operated member is arranged to engage said controlling member to cause actuation of the code signal formulating means only when said controlling member is abnormally positioned at the termination of a predetermined period starting with the initiation of such an operating cycle and measured by the running of the drum 117 and the parts moving therewith, the duration of which period substantially exceeds that of a shunt loop break incident to the actuation of any auxiliary station, such as the stations G, H, I and J; and that starting of the transmitter will be caused by the disengagement of the

detent 57 from the track 56 only when said drum is running in response to an energization of the magnet 62 the duration of which is such that said controlling member is normally positioned at the termination of such a period.

The various parts are normally positioned as shown by Figs. 1, 2 (solid lines), 3, 4 and 5; the current flow from the battery A is then through the normal path as follows:— from one terminal of battery A, through conductor 21, bell B, conductor 22, register C, and conductor 23 to the terminal 29 of transmitting station F. From terminal 29 to conductor 71 of said transmitting station, two parallel paths are provided as follows:—(1) through conductor 30, pivot 36, arm 35, and button 37 to conductor 31 at auxiliary station H, thence through conductors 31, 32 and 33 and similarly through corresponding parts of auxiliary stations J, I and G, through conductor 34, and terminal 28 to conductor 71 of transmitting station F; (2) through a portion of conductor 72, through conductor 74, the winding of the tripping magnet 62 and conductor 73 to said conductor 71. From the junction of conductors 71 and 73 the current path from the battery A continues through the remainder of conductor 71, to and through contacts 64 and 63, through conductor 70, contacts 52, conductor 69, winding of electromagnet 53, and conductor 68, to terminal 27 of transmitting station F; thence through conductors 24 and 25 and correspondingly through transmitting stations E and D, and through conductor 26 to the other terminal of the battery A.

It will be noted that the current path between terminal 29 and conductor 71 of station F which includes the winding of the electromagnet 62 has a resistance many times that the current path which includes the auxiliary stations H, J, I and G; it is therefore evident that nearly all of the current flow from the battery A will pass through said auxiliary stations, and that the current flow through the winding of the magnet 62 will be of negligible volume, and said magnet will therefore not be effectively energized.

The operation of the embodiment of this invention which is shown by the accompanying drawings is as follows:—when it is desired to cause the transmitting station F to act to formulate the code signal of its wheel 50, the push rod 45 of any one of the auxiliary stations G, H, I or J should be actuated. Assuming, for the sake of illustration, that the push rod 45 of station H is so actuated as to disengage the latch 42 from the pin 44; it is evident that the switch arm 35 will be moved by the spring 40 out of engagement with the button 37, over the buttons 38 and 39, and into engagement with the

stop 41; and that such movement of said arm will be appreciably retarded by the dashpot 47.

When said arm 35 has moved out of engagement with the button 37 and has not yet moved into engagement with the button 39, it is evident that the current path through the auxiliary stations G, H, I and J will be interrupted; thus restricting the entire current flow of the battery A through the winding of the tripping magnet 62 and thereby effectively energizing said magnet.

Upon such effective energization of the magnet 62, the armature 153 will be attracted thereby so as to act through the shaft 154 to carry an end of the bar 151 (see Figs. 4 and 5) into engagement with the arm 150, and thereby swing the arm 145 out of the path of the pin 146; whereupon the pressure of the pin 141 against the end 140 will swing said end out of the path of said pin and thus permit the escapement wheel 135 and the parts moving therewith to start. It will be noted that the pin 146 is normally pressing against the end of the arm 145 so that when said arm is moved out of the path of said pin, as just described, said pin will immediately move into the path of said arm and thereby prevent said pin from being so reengaged by said arm as to move or maintain the end 140 in the path of the pin 141.

Although the interruption of the shunt current path around the winding of the electromagnet 62 incidental to the movement of the switch arm 35 is of very short duration, it is of sufficient duration to insure effective energization of said magnet 62, so that the arm 145 will be momentarily withdrawn from the path of the pin 146, and at least one revolution of the escapement wheel 135 will thus be assured. During such revolution of the escapement wheel 135, a beveled end of the track 121 will pass outside of the lug 149, so as to act through said lug to hold the arm 145 in such position that the free end of said arm will be out of the path of the pin 146, and will thus prevent said arm from engaging said pin to arrest the running of the starting attachment until the notch 158 is again presented to the lug 149.

Inasmuch as the magnet 62 will be de-energized, because of the reestablishment of the shunt circuit through the auxiliary stations immediately after the release of the starting attachment, as just described, it is evident that the armature 153 will not oppose the pull of the spring 155, and the bar 151 will therefore swing out of engagement with the free end of the arm 150, thus permitting the spring 147 to swing the arm 148 so as to bring the lug 149 into engagement with the inner face of the track 121; to the end that, during ensuing rotation of the

drum 117, the block 122 will pass between the lug 149 and the shaft 100, and will therefore not engage said lug during such rotation of said drum.

During such rotation of the drum 117, the cam 120 will so swing the lever 123 as to bring the pin 130 into engagement with the shoulder of the terminal 131, and thereby so thrust the link 60 as to swing the detent 57 out of engagement with the track 56 so as to release the main line code signal transmitter.

The movement imparted to the lever 123 (see Fig. 3), as just described, will also cause the pin 130 to engage the slanting face of the hookarm 109 (see Fig. 2) so as to disengage said arm from the pin 110; whereupon the lever 80 will swing in response to the spring 83 and thereby carry the pin 82 out of the path of the contact 65 and carry 85 the shield 114 away from the indicator plate 67 so as to fully expose the legend "Not set".

When the pin 82 is moved out of the path of the contact 65, as just described, said contact will move into engagement with contact 66 and thus establish a short circuit around the winding of the electromagnet 62 as follows,—from conductor 74 which connects with one end of the winding of said magnet, through part of conductor 72 to contact 65, thence through said contact and through contact 66 to contact 64, through a part of conductor 71 and through conductor 73 which connects the other end of the winding of said magnet. The resistance of said magnet will therefore be excluded from the main line circuit, under the conditions just described regardless of the continued integrity of the shunt circuit through the auxiliary stations G, H, I and J.

After the rise of the cam 120 has served to cause the tripping of the main line transmitter, as just described, the continued rotation of the drum 117 will withdraw the rise of said cam from the path of the lever 123 and will thus permit said lever to return to its normal position in response to the pull of the spring 125, and the detent 57 will be moved into engagement with the track 56 by the tension of the spring 75 so as to be in position to arrest the running of the transmitter as soon as said mechanism has acted to formulate the intended code signal impulses in the main line circuit.

Referring now to Fig. 5: it will be seen that, when the parts therein shown are normally positioned, the block 122 is situated in advance of (above) the dog 159. After the drum 117 has turned around the shaft 100 for nearly one revolution, it is evident that the block 122 will approach the rear side of the dog 159 and swing said dog counter-clockwise, thus stretching the spring 163 so as to urge the piece 161 into engagement

with the projection 164 as shown by Fig. 7; it is therefore evident that when the projection 164 is withdrawn from the path of said piece 161, the circumferential face of said piece 5 will pass between said projection and the shaft 100 so as to maintain said projection in normal position, as shown in Fig. 8. As the trailing end of the track 121 is withdrawn from the path of the lug 149, the pin 10 157 will engage the ear 156 and thus cooperate with the spring 147 in swinging the arm 148 so as to carry the projection 164 out of the path of the segmental piece 161 and so as to move the arm 145 into the path 15 of the pin 146. The engagement of the pin 157 with the ear 156 will occur just after the escapement wheel 135 has carried the pin 141 to the right of the end 140, and said pin 20 157 will move out of the path of the ear 156 just before said escapement wheel has carried said pin 141 into position to again engage the end 140.

From the foregoing it will be seen that, regardless of the effectiveness of the short 25 circuit through contacts 65 and 66 or of the shunt circuit through the stations G, H, I and J, the rotation of the drum 117 will be positively arrested at the end of one revolution thereof, and that said drum will there- 30 after remain locked until the shaft 100 has been rotated for the purpose of rewinding the main spring 105.

During the running of the main line 35 transmitter, each revolution of the code wheel 50 will cause intended response of the bell B and register C; and, after the intended number of rotations of said code wheel, the detent 57 will reengage the track 56 and thus bring said transmitter to rest.

When it is desired to restore the various parts to their normal position after operating as just described,—the switch arm 35 of the actuated auxiliary station should be raised to its normal position, so that the pin 44 will be reengaged by the latch 42; and a winding key or other suitable restoring device should be applied to the squared end 101, and the shaft 100 rotated until its movement is arrested as hereinafter more fully explained.

Upon rotating the shaft 100, as just described, the boss 104 will turn therewith to store energy in the main spring 105 for future operation of the starting attachment; and the disk 106 (see Fig. 2) will rotate with said shaft 100 and thereby force the dog 107 away from said shaft. Such movement of said dog will swing the end of the flexible latch 115 out of the path of the pin 116 and will swing the arm 108 downwardly so that the free end of said arm will act through the pin 84 to swing the lever 80 to its normal position and thereby carry the pin 82 into engagement with the contact 65 and move said contact away from contact

66; and such movement of said arm will also carry the shield 114 across the upper portion of the indicator plate 67 so as to cover the word "Not" while leaving the word "Set" exposed. 70

During the rotation of the shaft 100, as just described, the pin 160 moving with said shaft will engage walls of the slots in the boss of the dog 159 so as to turn said dog with said shaft from the position shown in Fig. 8 to that shown in Fig. 5; whereupon the rotation of said shaft 100 will be arrested when said dog is brought into engagement with the rear side of the block 122. Just before the rotation of the shaft 100 is thus arrested, the notch in the disk 106 will be presented to the free end of the dog 107, and said dog will be moved into engagement therewith by the tension of the spring 111. The various parts will 80 85 thereupon be restored to their respective normal positions.

Should the current path through the auxiliary station shunt loop be interrupted for a comparatively extended period of time, as, for example, by the rupture of one of the conductors forming part of said loop,—the magnet 62 will be energized and will thereby cause the arm 145 to be withdrawn from the path of the pin 146, as hereinbefore more fully explained, whereupon the drum 117 and parts moving therewith will move through the cycle of action hereinbefore more fully described. Because of the continued energization of the magnet 62, the armature 153 will be maintained in fully attracted position until the lever 80 has moved to its abnormal position at the conclusion of the first half of a revolution of said drum; and the lug 149 will therefore be held in the path of the block 122, as best shown by Fig. 6. When the advancing end of the block 122 engages the lug 149, the slanting face of such end will swing said lug toward the shaft 100, thereby rotating the shaft 91 so as to carry the pin 92 (see Fig. 3) past the projection 93 and to bring the ear 94 into engagement with the link 60 and swing the shoulder of the terminal 131 out of the path of the pin 130. While the parts are thus positioned, the rise of the cam 120 will swing the lever 123 so as to carry the pin 130 past the shoulder of the terminal 131 along the upper flat face of said terminal. The subsequent rotation of the drum 117 (see Fig. 6) will withdraw the block 122 from engagement with the lug 149 and will cause the rise of the cam 120 to swing the lever 123 so as to move the pin 130 (see Fig. 2) along the inclined face of the hookarm 109 and thereby permit the lever 80 to move to its abnormal position, with the results hereinbefore more fully described. 115

120 After the lug 149 has been disengaged 125 130

by the block 122, as just described, the spring 147 will swing the lever 143 toward its normal position, thereby swinging the lever 90 toward the left (as seen in Fig. 3) 5 until the pin 92 engages the projection 93; but the tension of the spring 147 will be insufficient to thereby move the contact 63 away from the contact 64. During subsequent rotation thereof, the rise of the cam 10 120 will engage the lever 90 and thereby move said lever toward the normal position thereof, thus carrying the pin 92 past the end of the projection 93 to the position shown in Fig. 10; during which movement 15 the engagement of said pin with said projection will cause the contact 63 to be temporarily moved away from the contact 64. When the lever 90 has been moved by the cam 120, as just described, the magnet 62 20 will have been deenergized incident to the movement of the lever 80 upon disengagement thereof by the arm 109, and the spring 147 will therefore swing the lever 143 and parts moving therewith toward the normal 25 position thereof until the lug 149 is brought against the inner face of the track 121. Throughout succeeding rotation of the drum 117, the lug 149 will ride along the inner face of the track 121 until the notch 158 30 in said track is presented to said lug, whereupon said drum and the parts moving therewith will be brought to rest as hereinbefore more fully explained.

Upon each of the occasions when the pin 35 92 is moved past the projection 93, as just described, the contact 63 is moved away from the contact 64, and the current path of the battery A is thereby interrupted. It will therefore be evident that the bell B and 40 the register C will act twice (thereby manifesting the code signal 1-1) during the operation of the starting attachment in response to a continuing interruption of the auxiliary station shunt loop, and that said 45 current path will thereafter be closed, thus leaving the circuit conditioned for response to transmitting stations D and E, as well as to the operation of the transmitting mechanism of station F, should same be manually 50 set in motion.

Inasmuch as the actuation of the contact 63 by the pin 92, as just described, causes the manifesting devices B and C to repeatedly act and establishes a measured 55 pause between such actions in accordance with a previously determined code, as just described, for the purpose of manifesting a distinctive signal designating a fault in an auxiliary station loop, said parts will be 60 hereinafter referred to as "code signal formulating means".

Should it be desired that such code signal formulating means shall cause the manifestation of other than the signal 1-1, one 65 or more additional projections, such as the

projection 93, may be arranged, for example, as shown in Fig. 10, so that the signal formulated incident to the movement of said lever 90 in response to a continued interruption of the auxiliary loop will cause a 70 code signal such as 2-2, 3-3, or the like. If need be, the form of the lug 149 and that of the block 122 may be suitably altered so that a greater angular movement will be 75 imparted to the lever 90, and so that such movement will be distributed over a greater portion of the rotation of the drum 117, to the end that the movement of said lever will be better suited for the formulation of a 80 desired code signal. The details of such varied arrangements are not herein shown as they will readily suggest themselves to those who are skilled in this art and form no part of this invention other than in so far as such arrangements comprise the provision of code 85 signaling means operable incident to the running of the starting attachment subject to the conditioning of the tripping magnet. The term code signal, as herein used in relation thereto, being intended to signify one 90 or more groups of signaling impulses each of which impulses is of a character suited for causing individual response thereto by the manifesting devices connected in the main line circuit;—has distinguished from 95 signaling means such as that shown in my prior application hereinbefore cited, in which the signal formulated under like circumstances would cause but a single response 100 of the manifesting devices of a main line circuit, and would therefore not distinguish from the response of such instruments to rupture of the main line circuit or failure of the current source therefor.

After the current path through the auxiliary station shunt loop has been interrupted for an extended period, and it is believed that repairs have been made serving to restore said loop to its normal closed condition,—should it be desired to ascertain the 105 condition of said loop without causing the formulation of any signal in the main line circuit in the event that such shunt loop is not normally conditioned,—the shaft 100 110 should be rotated sufficiently to force the dog 107 far enough away therefrom to cause the arm 108 to move the lever 80 into engagement with the contact 65, (say about one-half of a revolution) but not far enough 115 to cause said arm to carry the pin 110 into register with the notch provided therefor in the arm 109. If the shunt loop is then in normal condition, the armature 153 will not move in response to such partial rotation of the shaft 100; but if said loop is open or 120 is closed through a poor connection so that the resistance of said loop is excessive, said armature will move toward the magnet pole pieces 152, 152 and thereby give warning 125 that the direction of rotation of the shaft 130

100 should be reversed, thus allowing said shaft to turn in response to tension of the spring 105 until the rotation thereof is arrested by the engagement of the dog 107 with the notch of the disk 106.

In the event of the energization of the magnet 62 in response to a partial rotation of the shaft 100, as just described, the lever 143 will not be so moved as to disengage 10 the arm 145 from the pin 146, because the segmental piece 161 will remain in the path of the projection 164 carried by the arm 148 and will thereby prevent release of the starting attachment in response to such energization of said magnet.

From the foregoing it will be seen that the operation of this improved starting attachment in response to intended actuation of a suitable auxiliary station will result in 20 tripping the associated main line transmitter; and that the operation of said attachment in response to a continued interruption of said auxiliary loop will not cause the operation of said main line transmitter but 25 will directly formulate a code signal in the main line circuit such as will cause response of the bell B and register C differing from that incident to the operation of the main line transmitting mechanism of any station 30 (such as the stations D, E and F), and so differing from the single stroke sounded by said bell and the one mark upon the tape of said register in response to a continuing break of the main line circuit such as would 35 result, for example, from accidental rupture of one of the conductors of said circuit, as to be readily distinguishable therefrom.

The illustrative embodiment of this invention shown by the accompanying drawings and hereinbefore described in detail is given for the purpose of enabling this invention to be more readily understood; but this invention is not limited to the particular arrangement there shown and hereinbefore described in detail;—as many changes may be made in construction and arrangement, and parts may be added or omitted without departing from the spirit of this invention, the scope of which is indicated by 50 the following claims:—

1. An attachment comprising means for functional operation in response to an auxiliary circuit to cause starting of a main line transmitter only when said means is 55 preconditioned for such operation, an indicator movable from set to unset position upon functional operation of said means, and latch means for said indicator so governed by said first named means as to prevent resetting of said indicator other than when such preconditioning of said first named means has been restored.

2. In a starting attachment for a signal transmitter,—a windable part, a holder arranged for retaining said part in fully

wound condition and for abnormal positioning thereof during winding of said part, indicator mechanism biased to act to manifest need of winding of said part, means operable by movement of said holder incident to 70 winding of said part for actuating said mechanism in opposition to said bias; a latch for retaining said mechanism in actuated position, means operable by the running of said attachment for disengaging said latch 75 from said mechanism, and a detent so associated with said indicating mechanism as to normally prevent actuation thereof in opposition to said bias to the position where it may be held by said latch and so associated 80 with said holder as to be conditioned to permit such actuation of said mechanism only during abnormal positioning of said holder.

3. In a starting attachment for a main line signal transmitter,—a motor spring for 85 actuating said attachment, a winding member for said spring, an actuator operable incident to the unwinding of said spring for starting said transmitter, an indicator biased for movement to abnormal position, a latch 90 for retaining said indicator in normal position, a detent for preventing movement of said indicator from abnormal to normal, means moved by the running of said attachment for disengaging said indicator from 95 said latch, and means moved by the actuation of said winding member for withdrawing said detent from the path of said indicator and for moving said indicator from abnormal to normal.

4. In a starting attachment for a main line signal transmitter provided with a tripping magnet arranged to be shunted by an auxiliary station loop,—code signal formulating means subject to actuation by said attachment; electrical conductors serially connecting said transmitter, said tripping magnet and said formulating means; transmitter starting means operable by the running of said attachment; normally wound driving means for said attachment; a restoring member operable for rewinding said driving means; a holder for said member; indicator mechanism biased to act to manifest need of winding of said part, means operable by 100 movement of said holder incident to winding of said part for actuating said indicating mechanism in opposition to said bias; a retainer for holding said indicating mechanism in actuated position; means operable by the running of said attachment for causing the release of said indicator mechanism from said retainer; a latch operable by said holder for preventing movement of said indicator mechanism to said actuated position 105 other than during actuation of said restoring member, and means for causing functional actuation of said signal formulating means in the event of operation of said attachment such as to require rewinding of said driving 110

means without thereby causing operation of the transmitter starting means.

5. In a starting attachment for a signal transmitter comprising a tripping magnet for connection in an auxiliary loop,—a normally wound train involving a tripper actuating part, a detent responsive associated with said magnet and arranged for arresting movement of said part after a predetermined cycle of the operation thereof, a member operable independently of said part to store energy for driving said part, and means so jointly controlled by said part and said member as to mechanically act after each operative cycle thereof to condition said detent to prevent further movement of said part until said member has thereafter been so operated as to store sufficient energy for another operative cycle of said part.
- 10 6. In a starting attachment for a main line signal transmitter,—a normally wound train involving a tripper actuating part, a detent arranged for arresting movement of said part after a predetermined cycle of the operation thereof, a member operable independently of said part to store energy for driving said part, means for assuring a full cycle of the operation of said part whenever said detent is conditioned to permit actuation thereof, means moved by the running of said train for effectively conditioning said detent at the conclusion of each such cycle, and a holder so jointly controlled by said part and said member as to mechanically act after each operative cycle of said part to condition said detent to prevent further movement of said part until said member has thereafter been so operated as to store sufficient energy for another operative cycle of said part.
- 15 7. In a normally wound starting attachment for a main line signal transmitter provided with a tripping magnet arranged to be shunted by an auxiliary station loop, a normally wound train involving a tripper actuating part and a member operable independently thereof to store energy for driving said part, a detent for said train controlled by said magnet, means moved by the runnings of said train for temporarily preventing reengagement of said detent after disengagement thereof, a restoring member moved by the running of said train after a predetermined cycle thereof for moving said detent to effective position, a holder for retaining said detent in effective position, means moved by said train in running for moving said holder into the path of said detent whenever said detent is moved to its effective position at the conclusion of a cycle of the operation of said train, and means moved by said windable member for withdrawing said holder from the path of said detent.
- 20 8. In a normally wound starting attach-

ment for a main line signal transmitter provided with a prewinding member operable to store energy for driving said attachment and a tripping magnet arranged to be shunted by an auxiliary station loop,—a tripping member for said attachment controlled by said magnet, means for preventing said tripping member from acting to stop the running of said attachment after starting thereof until said attachment has run for a predetermined cycle, means operable by said attachment in running for moving said tripping member for the purpose of arresting the running of said attachment after the completion of such predetermined cycle, and a holder for said tripping member so jointly controlled by said attachment and said prewinding member as to permit movement of said tripping member to trip said attachment after the completion of such a cycle of the running thereof only after said prewinding member has been so operated as to store sufficient energy for another operative cycle of said attachment.

25 9. In a starting attachment for a main line transmitter,—a winding shaft, ratchet means for retaining winding movement imparted to said shaft, a motor spring one end of which is secured to said shaft, a drum revoluble independently of said shaft and to which the other end of said spring is attached, a dog loosely journaled upon said shaft and so connected therewith as to permit limited relative movement therebetween, a lug carried by said drum and moving in the path of said dog whereby relative movement between said shaft and said drum is suitably limited, a detent lever for preventing rotation of said drum, means operable by the rotation of said drum for preventing movement of said detent to its effective position prior to the completion of an intended operative cycle of said drum, means moved by the rotation of said drum for moving said detent to its effective position at the conclusion of such an operating cycle, a holder for retaining said detent in its effective position, means actuated by the rotation of said drum for urging said holder into engagement with said detent, and means operable by said windable part for disengaging said holder from said detent.

30 10. In a starting attachment for a main line signal transmitter,—a winding shaft; ratchet means for retaining winding movement imparted to said shaft; a motor spring one end of which is secured to said shaft; a drum revoluble independently of said shaft and to which the other end of said spring is attached; a dog loosely journaled upon said shaft and so connected thereto as to permit limited relative movement therebetween; a lug carried by said drum and moving in the path of said dog whereby relative movement between said shaft and said drum

is suitably limited; a detent lever for preventing rotation of said drum; means for continuing the ineffectiveness of said detent lever after movement thereof from normal 5 to abnormal position until the conclusion of the full intended rotation of said drum; a segmental plate revoluble around said shaft independently of said shaft, said drum and said dog; a spring connecting said plate 10 and said dog; and such relative arrangement and formation of said lug, said dog, said detent lever and said plate that when said main spring is normally wound said plate will permit movement of said detent lever 15 from normal to abnormal position, so that—

when said detent lever is abnormally positioned—a projection therefrom will extend into the path of said plate, so that—after intended rotation of said drum following release thereof—said lug will move said dog 20 so as to apply tension of said second named spring tending to swing said plate into the path of said detent lever, and so that movement of said lever from normal to abnormal position will be prevented when said plate 25 has been so swung.

In witness whereof, I hereunto subscribe my name, this 24th day of June, 1921.

NATHAN H. SUREN.
